UNITED STATES PATENT OFFICE.

CHRISTIAN W. MEINECKE, OF JERSEY CITY, NEW JERSEY, ASSIGNOR TO MEINECKE & COMPANY, OF NEW YORK, N. Y., A CORPORATION OF NEW JERSEY.

DESIGN FOR A SURGICAL BASIN.

46,262.

Specification for Design.

Patented Aug. 11, 1914.

Application filed May 27, 1914. Serial No. 841,390. Term of patent 7 years.

To all whom it may concern:

Be it known that I, CHRISTIAN W. MEINECKE, a citizen of the United States, residing in Jersey City, in the county of Hudson and State of New Jersey, have invented a new, original, and ornamental Design for Surgical Basins, of which the following is a specification, reference being had to the accompanying drawing, forming part thereof, in which—

Figure 1 represents a perspective view of

a surgical basin embodying this design. Fig. 2 is a plan view thereof. Fig. 3 is a side elevation of the same.

I claim:

The ornamental design for a surgical basin, as shown.

CHRISTIAN W. MEINECKE.
